United States Patent Office

Des. 219,261
Patented Nov. 24, 1970

219,261

BOTTLE

Robert A. Barish, East Windsor, N.J., assignor to Johnson
& Johnson, a corporation of New Jersey

Filed Dec. 15, 1969, Ser. No. 20,500

Term of patent 14 years

Int. Cl. D9—01

U.S. Cl. D9—143

FIG. 1.

FIG. 2.

FIG. 3.

FIG. 1 is an elevational view of a bottle showing my new design, the opposite side being the same in appearance as the side shown;

FIG. 2 is an elevational view looking from the right of FIG. 1, the opposite side being the same in appearance as the side shown; and

FIG. 3 is a top plan view thereof.

I claim:

The ornamental design for the bottle, as shown and described.
